UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed May 1, 1922. Serial No. 557,661.

My invention relates to mining machines. It has for its object to provide an improved cutter chain driving mechanism for such a machine and improved cooperating feeding and feed controlling mechanism therefor, whereby the operation of the machine is materially improved and whereby the mechanism is materially simplified and rendered more flexible in operation. These and other objects and advantages of my improved construction will, however, hereinafter more fully appear.

In the accompanying drawings I have shown for purposes of illustration one embodiment which my invention may assume in practice.

In these drawings,—

Fig. 1 is a plan view partially in section of a mining machine constructed to provide an illustrative embodiment of my invention.

Fig. 2 is a side elevation partially in section of the mechanism shown in Fig. 1.

Fig. 3 is a detail sectional view on line 3—3 of Fig. 1.

Fig. 4 is a detail sectional view on line 4—4 of Fig. 2.

In this illustrative construction I have shown a mining machine of the room and pillar type comprising a casing 1 slidable on its bottom 2 on the mine bottom and carrying a cutter bar 4 provided with the usual circulating cutter bit carrying cutter chain 5 and having feeding mechanism which will be hereinafter described, the feeding mechanism and cutter chain driving mechanism being driven from a motor 6 through driving connections also hereinafter described.

In describing my improved construction, I will first describe the cutter chain driving mechanism. The cutter chain 5 is driven by a driving sprocket 8 rotatable on a vertical axis adjacent the rear end of the machine. Here it will be noted that the armature shaft of the motor 6 is provided with a beveled pinion 9 in turn meshing with a horizontally disposed larger bevel gear 10 rotatable on a ball bearing 10' concentric with a vertical stud 11 on the rear end of the frame. This gear 10 is in turn connected as through nuts 12 to a sleeve carrying a lower pinion 13 which in

turn meshes with a plurality of, herein three, radially located pinions 14 journaled in suitable ball bearings 15 on a spider 16, while the pinions 14 mesh with an internal gear 17 attached as by screws 18 to the sprocket member 55 8 and which with that member is journaled on roller bearings 19, herein located between ball bearings 20, so as to rotate relative to the spider and the lower end of the stud. As shown, the spider is also provided with an up-standing sleeve 21 rotatable on the stud inside the sleeve carrying the pinion 13, and suitable bearing sleeves 22 and 23 are provided on the opposite sides of this sleeve 21 while the roller bearings are enclosed in suitable sleeves 24 60 and 25. A flanged ring 26 is also interposed between the lower roller bearing 19 and the lower ball bearing 20, while a retaining member 27, flush with and attached to the bottom plate by suitable screws 28 and to a reduced 65 portion 29 on the stud by a suitable screw 30, is provided to hold the parts in the desired assembled relation. As illustrated, the gear 17 is also provided with a friction surface 31 70 on its periphery acted upon by a brake band 32 which is in turn controlled by a rotating nut and bolt connection 33 having its bolt projecting into the nut on the outside of the frame, herein adjacent the feed operating member, and having its nut rotated by a 75 hand wheel 34.

Cooperating with this mechanism is the feeding mechanism. This mechanism is herein connected to and driven by the sleeve 21 on the spider, the same being connected 80 through a clutch connection 35 acting semi-permanently to connect this sleeve with a worm carrying sleeve 36 rotatable on the upper end of the stud relative to a flanged bearing sleeve 37, the bearing 10', and a ball 85 bearing 38 removable through the top of the machine frame and, upon removal of a cap 39, acting as a support for the reduced upper end 40 of the stud and screwed thereto by a screw 41 and to the casing by screws 42. This worm 36 in turn meshes with a worm gear 43 disposed on a transverse axis located in rear of the stud. As shown, this worm gear rotates with the casing 44 of a differential, herein comprising series of beveled gears, herein 90 95 100

three, 45 carried on a spider 46 and meshing with oppositely disposed bevel gears 47 and 48 rotatable on a transverse shaft 49. As shown, the gears 45 are suitably journaled on ball bearings 50 on the spider studs, the spider is keyed to the shaft 49 as at 51, and the gears 47 and 48 are carried on sleeves 52 and 53, suitably journaled in ball bearings 54 disposed between the same and the differential casing. As shown herein, the sleeve 52 is also keyed as at 55 to the hub of a friction pulley 56 the rotation of which is controlled by a suitable brake band 57 through a controlling member 58, while the sleeve 52 is also connected through a semi-permanent clutch 59 with a sleeve 60. This sleeve 60 which is journaled in a suitable bushing 61 carries at its outer end a spur pinion 62 which meshes with an internal gear 63 upon a suitable drum member 64 journaled in an appropriate manner upon the left hand side of the machine frame 1. Also it will be noted that the sleeve 53 is keyed as at 65 to the hub of a friction pulley 66 controlled by a brake band 67 operated by a controlling member 68 and that this sleeve 53 is connected through a semi-permanent clutch 69 with a sleeve 70. The sleeve 70 likewise carries at its outer end a driving pinion 71 meshing with an internal gear 72 and journaled in a suitable bushing 73. The internal gear 72 is formed upon a drum member 74 suitably journaled on the right hand side of the machine frame 1. Appropriate holding means, indicated at 75, are provided for the purpose of holding the sleeves 60 and 70 in appropriate longitudinal position relative to the shaft 49.

Cooperating with the drums 64 and 74 are suitable flexible feeding members 78 and 79 which are respectively secured at one end to the drums 64 and 74 while the other end of the cable 78 passes forward along the left hand side of the machine during right to left cutting and around a suitable guide sheave 80 rotatably mounted at the front end of the frame 1, while also the member 79 passes rearwardly along the right hand side of the machine and around a guide sprocket 81 and off to a suitable takeup member adjacent the right hand rib. In order to permit the machine to cut in opposite directions there are provided additional guiding sprockets 82 and 83 corresponding respectively to the sprockets 81 and 80 and arranged respectively at the opposite sides of the machine frame from their corresponding sheaves. It will be understood that the flexible members 78 and 79 may be wound in either direction on their respective drums and may be variously reeved relative to the sheaves 80, 82 and 81, 83.

The mode of operation of this mechanism when cutting across a face from right to left may now be described and from this description one skilled in the art will be able to understand the operation of the machine under

other conditions. Let it be assumed that the machine has been sumped into the coal and straightened up to the face, that the rear end of the flexible feeding member 79 is connected to a take-up member adjacent the right hand rib and that the forward end of the member 78 is connected to a jack adjacent the left hand rib and relatively close to the face. The cutter chain must circulate under these circumstances in a counter-clockwise movement through its orbit. It will therefore be found that, looking forward, the bevel pinion 9 upon the armature shaft is rotating in a counter-clockwise direction, driving the pinion 10 in a clockwise direction viewed from above. This causes the gear 13 to rotate in a clockwise direction viewed from above and the latter drives the several pinions 14 in a counter-clockwise direction, causing them to drive the internal gear 17 which is connected as previously described to the cutter chain driving sprocket 8 in a counter-clockwise direction so that the cutter chain is rotated in the necessary direction. During cutting the cutter chain of course presents a substantial resistance to being dragged through the coal and accordingly the gear 17 does not rotate as rapidly as would be possible were there no resistance opposed to its rotation. It therefore follows that the gears 14 being unable to drive the gears 17 at a speed equal to their peripheral speed, roll in a clockwise direction around the internal gear carrying with them the spider member 16 which is connected to the worm 36 and causing thereby the worm 36 to rotate in a clockwise direction. It will be observed from Fig. 2 that this worm has a left hand thread and as a result it causes the worm wheel 43 to rotate in a counter-clockwise direction as seen in Fig. 2. If the two pinions 62 and 71 present equal resistances to rotation, the drums 64 and 74 will be rotated in the same direction and at equal speeds and in view of the way in which the rope is wound upon the drums it will be found that the drum 64 will rotate in a direction to wind in the flexible portion 78 while the drum 74 will rotate in a direction to pay out the flexible portion 79. Accordingly, the machine would be moved across the face while maintained perpendicular to the face. It will be observed that the rope 78 must be under a substantial tension in order to move the machine, which tension resists the rotation of the drum 64 while the pulling of the machine across the face places the rope 79 under a tension which tends to aid the rotation of the drum 74. It is therefore evident that the drums would not rotate in the same direction and at equal speeds due to the presence of the differential unless the friction member 66 were loaded to the extent necessary to cause a resistance to rotation in the case of the pinion 71 equal to that in the case of the pinion 62. This is therefore done and the machine then moves across the face

in the manner described. By virtue of the construction just described it will be evident that by tightening the brake band 67 still further, the speed of rotation of the pinion 62 may be increased above that of the pinion 71. There will accordingly result a more rapid winding in of the flexible portion 78 than the paying out of the flexible portion 79. Accordingly, the bar will move forward more rapidly and the machine will be angled in one direction. By slackening off the friction upon the member 66, the drum 74 may be caused to turn more rapidly than the drum 64 which will permit the machine to angle in the opposite direction.

It will thus be evident that by the suitable manipulation of the controlling member 68 the movement of the machine across the face may be readily controlled. It will be evident, moreover, that by completely locking either the member 66 or the member 56, there may be accomplished a rotation of the drums twice as rapid as when they are rotating at the same speed, thereby permitting a more rapid movement during shifting of the machine from place to place and during sumping. Moreover, when a very rapid movement of the machine is desired, this is easily obtained by manipulation of the controlling mechanism 33 in such manner as to lock the cutter chain entirely, a relatively high speed of movement of the machine frame over the mine bottom then being possible. During cutting from left to right, the motor will obviously be reversed which will cause, without any change in the direction of winding of the flexible members upon the drums, paying out of the flexible member 78 and winding in of the flexible member 79. By virtue of the disposition of the members 80 and 82, and 81 and 83, it will be readily possible to carry the member 78 back from the member 80, around the member 82 and off to a take-up member at the left hand rib, while the member 79 may be carried forward and around the member 83. That is to say, while the flexible portions 78 and 79 are left extending around the guide sheaves with which they are shown cooperating in Fig. 1, they may be caused to leave the machine frame at the opposite ends of the latter from their present disposition with the result that the machine will be appropriately guided when cutting from left to right. Other possibilities as to the operation of this mechanism will readily present themselves to one skilled in this art and accordingly it seems unnecessary to provide a more detailed discussion.

While I have in this application specifically described one form which my invention may assume in practice, it will be understood that this form of the same is shown for purposes of illustration and that the invention may be modified and embodied in

various other forms without departing from its spirit or the scope of the appended claims.

What I claim as new and desire to secure by Letters Patent is:

1. In a mining machine, feeding mechanism therefor including a differential having orbitally movable elements and controllable to vary the feed, cutting mechanism including orbitally moving elements, and driving means for said mechanisms including a motor and mechanical connections between said motor and said mechanisms for automatically decreasing the speed of orbital movement of the elements of one upon an increase in speed of orbital movement of the other. 70 75 80

2. In a mining machine, feeding mechanism therefor including a differential having orbitally movable elements and controllable to vary the feed, cutting mechanism including orbitally movable elements, a motor, and power transmitting connections between said motor and said mechanisms for driving the orbitally movable elements of the latter at inversely varying speeds. 85 90 95

3. In a mining machine, mechanism for effecting lateral feed including flexible feeding means, a rotatable feed operating member cooperating therewith, and differential means including orbitally movable elements and controllable to vary the speed and power transmitted to said member, cutting mechanism including orbitally movable elements, a motor, and power transmitting connections between said motor and the orbitally movable elements of said mechanisms for effecting the supply of power thereto in inverse ratio. 100 105 110

4. In a mining machine, mechanism for effecting lateral feed and controlling machine angle during the cutting operation including flexible feeding means having advance and receding flexible feeding portions extending in opposite directions from opposite ends of the machine, feed operating and controlling members cooperating respectively with said flexible feeding portions, a motor, and power transmission connections between said motor and said feed operating and controlling members including a variable speed device for effecting drive at any speed between zero and a predetermined maximum, and a single differential driven by said variable speed device and through which said members are driven, said differential being controllable to effect rotation of said members at inversely varying speeds. 115 120 125

5. In a mining machine, feeding mechanism for effecting lateral feed and controlling machine angle including flexible feeding means, rotatable feed operating and controlling members cooperating with said flexible feeding means, and differential means controllable to vary the power distribution to said members, cutting mechanism, a mo- 130

tor, and power transmitting connections between said motor and said feeding and cutting mechanisms for effecting operation thereof at inversely varying speeds.

- 5 6. In a mining machine, cutting mechanism, feeding mechanism for feeding the machine in a direction parallel to a working face during cutting, and driving means for said mechanisms including a motor and power transmission connections between said motor and said mechanisms for driving the latter at inversely varying speeds, said feeding mechanism comprising a differential including elements movable in an orbit upon transmission 10 of power thereto by said motor.

- 15 7. In a mining machine, cutting mechanism, feeding mechanism for feeding the machine in a direction parallel to a working face during cutting, driving means for said mechanisms including a motor and power transmission connections between said motor and said mechanisms for driving the latter at inversely varying speeds, said feeding mechanism comprising a differential including elements movable in an orbit upon transmission 20 of power thereto by said motor, and friction means for controlling the rotation of the elements of the latter.

- 25 8. In a mining machine, cutting mechanism, feeding mechanism for feeding the machine in a direction parallel to a working face during cutting, driving means for said cutting and feeding mechanisms including a motor and power transmission connections 30 between said motor and said cutting and feeding mechanisms for driving the latter at inversely varying speeds, said feeding mechanism comprising a differential, and feed operating and controlling members operatively connected to separate elements of the differential.

- 40 9. In a mining machine, cutting mechanism, feeding mechanism for feeding the machine in a direction parallel to a working face during cutting, driving means for said cutting and feeding mechanisms including a motor and power transmission connections 45 between said motor and said cutting and feeding mechanisms for driving the latter at inversely varying speeds, said feeding mechanism comprising a differential, feed operating and controlling members operatively connected to the differential, and independent controlling means for said members.

- 45 10. In a mining machine, cutting mechanism, feeding mechanism for feeding the machine in a direction parallel to a working face during cutting, driving means for said cutting and feeding mechanisms including a motor and power transmission connections 50 between said motor and said cutting and feeding mechanisms for driving the latter at inversely varying speeds, said feeding mechanism comprising a differential, feed operating and controlling members operatively con-

nected to the differential, and independent friction controlled controlling means for said members.

11. In a mining machine, cutter chain driving mechanism connected to one element of a frictionally controlled planetary gearing through which said cutter chain is driven, and feeding mechanism connected to another element thereof and including a differential. 70

12. In a mining machine, cutter chain driving mechanism connected to one element of a frictionally controlled planetary gearing, feeding mechanism connected to another element thereof including a differential, and a feed operating member and a controlling member operatively connected to different elements of said differential. 75

13. In a mining machine, cutter chain driving mechanism connected to one element of a frictionally controlled planetary gearing, feeding mechanism connected to another element thereof including a differential, a feed operating member and a controlling member operatively connected to different elements of said differential, and independent controlling 80 means for said members. 85

14. In a mining machine, cutter chain driving mechanism connected to one element of a frictionally controlled planetary gearing, feeding mechanism connected to another element thereof including a differential, a feed operating member and a controlling member operatively connected to different elements of said differential, and independent frictionally controlled controlling means for said 90 members. 95

15. In a mining machine, cutter chain driving mechanism connected to one element of a frictionally controlled planetary gearing, worm gearing connected to another one of the elements thereof, a differential driven by said worm gearing, and feeding mechanism driven by said differential. 105

16. In a mining machine, cutter chain driving mechanism connected to one element of a frictionally controlled planetary gearing, worm gearing connected to another one of the elements thereof, a differential driven by said worm gearing, and feeding mechanism driven by said differential including independently controlled feed operating and controlling members. 110

17. In a mining machine, cutter chain driving mechanism connected to one element of a frictionally controlled planetary gearing, worm gearing connected to another one of the elements thereof, a differential driven by said worm gearing, and feeding mechanism driven by said differential including a frictionally controlled feed operating and a frictionally controlled controlling member. 120

18. In a mining machine, cutter chain driving mechanism connected to one element of a frictionally controlled planetary gearing, worm gearing connected to another one of the 125

elements thereof, a differential driven by said worm gearing, feeding mechanism driven by said differential including a frictionally controlled feed operating and a frictionally controlled controlling member, and flexible feeding means cooperating with said members.

19. The combination with a mining machine, of cutter chain driving mechanism connected to one element of a frictionally controlled planetary gearing, worm gearing connected to another one of the elements thereof, a differential driven by said worm gearing, feeding mechanism including feed operating and controlling members driven by said differential, and flexible feeding means cooperating with said members and having portions extending in opposite directions from opposite sides of said machine.

20. In a mining apparatus, mechanism for feeding a machine of the room and pillar type and for controlling its angle to a working face including a plurality of feed operating and controlling members adapted to cooperate directly with flexible feeding means, and driving mechanism for said members including a variable speed differential mechanism and a differential driven thereby, said differential having corresponding elements operatively connected to the feed operating and controlling members.

21. In a mining apparatus, mechanism for feeding a machine of the room and pillar type and for controlling its angle to a working face including a plurality of feed operating and controlling members adapted to cooperate directly with flexible feeding means, and driving and controlling mechanism for said members including a variable speed differential mechanism and a differential driven thereby, said differential having corresponding elements operatively connected to the feed operating and controlling members and means for controlling the rotation of said members.

22. In a mining apparatus, mechanism for feeding a machine of the room and pillar type and for controlling its angle to a working face including a plurality of feed operating and controlling members adapted to cooperate directly with flexible feeding means, and driving and controlling mechanism for said members including a variable speed differential mechanism and a differential driven thereby, said differential having corresponding elements operatively connected to the feed operating and controlling members and means for retarding the rotation of said members.

23. The combination with a mining machine, of cutting mechanism, feed operating and controlling mechanism including a differential having corresponding elements driving different feed operating and controlling members, and means for driving said differ-

ential at different speeds inversely proportional to speeds of the cutting mechanism.

24. In a mining apparatus, mechanism for feeding a machine of the room and pillar type and for controlling its angle to a working face including feed operating and controlling means on the machine including a motor, a differential, worm and worm gear driving mechanism therefor, and means driven by said motor for rotating said worm at widely different speeds between zero and a predetermined maximum while said motor speed remains constant.

25. In a mining apparatus, mechanism for feeding a machine of the room and pillar type bodily laterally over the mine bottom during the cutting operation and for controlling its angle to a working face including a feed operating member and a controlling member, flexible feeding means cooperating with said members including advance and receding flexible feeding portions extending in opposite directions from opposite ends of the machine, variable speed means through which both of said members are driven for effecting drive thereof at any speed between zero and a predetermined maximum, and means driven through said variable speed means and automatically operative upon retardation of one member to increase the speed of operation of the other.

26. In a mining apparatus, mechanism for feeding a machine of the room and pillar type bodily laterally over the mine bottom during the cutting operation and for controlling its angle to the working face including a feed operating member and a controlling member, flexible feeding means cooperating with said members including advance and receding flexible feeding portions extending in opposite directions from opposite ends of the machine, variable speed means through which both of said members are driven for effecting drive thereof at any speed between zero and a predetermined maximum, and means driven through said variable speed means and automatically operative upon retardation of either member to increase the speed of the other.

27. In a mining apparatus, mechanism for feeding a machine of the room and pillar type bodily laterally over the mine bottom during the cutting operation and for controlling its angle to a working face including a feed operating member and a controlling member, flexible feeding means cooperating with said members including advance and receding flexible feeding portions extending in opposite directions from opposite ends of the machine, variable speed means through which both of said members are driven for effecting drive thereof at any speed between zero and a predetermined maximum, and means driven through said variable speed means and automatically operative upon an increase in speed

of said controlling member to decrease the speed of said feed operating member.

28. In a mining apparatus, mechanism for feeding a machine of the room and pillar type bodily laterally over the mine bottom during the cutting operation and for controlling its angle to a working face including a feed operating member and a controlling member, flexible feeding means cooperating with said members including advance and receding flexible feeding portions extending in opposite directions from opposite ends of the machine, variable speed means through which both of said members are driven for effecting drive thereof at any speed between zero and a predetermined maximum, and means driven through said variable speed means and automatically operative upon an increase in speed of either member to decrease the speed of the other.

29. In a mining apparatus, mechanism for feeding a machine of the room and pillar type and for controlling its angle to a working face including a plurality of feed operating and controlling members, driving gearing therefor including a differential having corresponding elements connected to said feed operating and controlling members, and means manually controllable to effect rotation of said differential at any speed from zero to a given maximum.

30. In a mining machine, feeding mechanism therefor including a differential having orbitally movable elements and controllable to vary the feed, cutting mechanism including orbitally movable elements, and driving means for said mechanisms including a motor and mechanical connections between said motor and said orbitally movable elements for automatically decreasing the speed of certain of said orbitally movable elements upon an increase in speed of the other orbitally movable elements.

31. In a mining machine, feeding mechanism therefor including a differential having orbitally movable elements and controllable to vary the feed, cutting mechanism including cutting devices and driving means therefor including orbitally movable driving elements, a motor, and mechanical power transmitting connections between said motor and said mechanisms for driving the orbitally movable elements of the latter at inversely varying speeds.

32. In a mining machine, mechanism for effecting lateral feed including flexible feeding means, a rotatable feed operating member cooperating therewith, and differential means including orbitally movable elements and controllable to vary the speed and power transmitted to said member, cutting mechanism including cutting devices and driving means therefor including orbitally movable driving elements, a motor, and mechanical power transmitting connections between said

motor and the orbitally movable elements of said mechanisms for effecting the supply of power thereto in inverse ratio.

33. In a mining machine, cutting mechanism, feeding mechanism for feeding the machine in a direction parallel to a working face during cutting, and driving means for said mechanisms including a motor and mechanical power transmission connections between said motor and said cutting and feeding mechanisms for driving the latter at inversely varying speeds, said feeding mechanism comprising a differential including elements movable in an orbit upon transmission of power thereto by said motor.

34. In a mining apparatus, mechanism for feeding a machine of the room and pillar type and for controlling its angle to a working face including feed operating means on the machine including relatively rotatable feed operating and controlling members, a motor, a differential, said feed operating and controlling members being connected to different elements of said differential, worm and worm gear driving mechanism therefor, and means driven by said motor for rotating said worm at widely different speeds and any intermediate speed while said motor speed remains constant.

35. In a mining machine, cutter chain driving mechanism connected to one element of a planetary gearing, feeding mechanism connected to another element thereof including a differential, and a feed operating member and a controlling member operatively connected to different elements of said differential.

36. In a mining machine, cutter chain driving mechanism connected to one element of a planetary gearing, feeding mechanism connected to another element thereof including a differential, a feed operating member and a controlling member operatively connected to different elements of said differential, and independent frictionally controlled controlling means for said members.

37. In a mining machine, cutter chain driving mechanism connected to one element of a planetary gearing, feeding mechanism connected to another element thereof including a differential, a feed operating member and a controlling member operatively connected to different elements of said differential, and independent frictionally controlled controlling means for said members.

In testimony whereof I affix my signature.
MORRIS P. HOLMES.
